UNITED STATES PATENT OFFICE.

GERALD W. HART, OF WEST HARTFORD, CONNECTICUT, ASSIGNOR TO THE HART MANUFACTURING COMPANY, OF HARTFORD, CONNECTICUT, A CORPORATION OF NEW JERSEY.

SWITCH.

1,103,199.

Specification of Letters Patent.

Patented July 14, 1914.

Application filed November 26, 1913. Serial No. 803,144.

To all whom it may concern:

Be it known that I, GERALD W. HART, a citizen of the United States, residing at West Hartford, Hartford county, Connecticut, 5 cut, have invented certain new and useful Improvements in Switches, of which the following is a full, clear, and exact description.

My invention relates to improvements in switches, and has for its object to produce a 10 new and improved auxiliary circuit breaker for making and breaking at the proper times closing and opening circuits of a remote-controlled switch.

It also has for its object to produce an auxiliary circuit breaker in which neither of the 15 making or breaking actions are produced directly by the closing or opening movement of the main switch arm or parts rigidly connected thereto.

It also has for its object to produce an auxiliary circuit breaker in which turning of the contacts will not be liable to interfere with its action.

It also has for its object to secure the 20 various advantages arising from the combination hereinafter described and particularly referred to in the claims.

The following is a description of an embodiment of my invention, reference being 25 had to the accompanying drawings, in which—

Figure 1 shows a plan view of a remote-controlled switch embodying my invention. Fig. 2 shows a longitudinal vertical section 30 of the same on the line 2—2 Fig. 1. Fig. 3 shows a vertical section of the releasing coil of the remote-controlled switch, together with the locking device and the auxiliary circuit breaker, on the line 3—3 Fig. 4. Fig. 4 is a plan view of the circuit breaker. Fig. 5 is a similar view, with the armature removed. Fig. 6 is a sectional view on the line 6—6 Fig. 4. Fig. 7 is a diagram of circuits.

Referring more particularly to the drawings, 1 is an insulating base having contacts 2—2' adapted to be connected by switch arms 3. These switch arms are connected to a cross-bar 4 so as to be insulated therefrom. From this cross-bar depend magnetic cores 5, against which act springs 6 normally tending to lift the same, together with the switch arms 3—3.

7—7 are stops limiting the upward movement of the switch arms.

8—8 are solenoids which when energized act to draw the cores 5 and the switch arms connected thereto downwardly so as to close the switch. Secured to the bar 4 is a downward projection 9 having a bore within 60 which is located a movable plunger 10. The upper end of the bore is enlarged so as to contain a spring 11, which bears upon a flange 12 connected to the plunger, and tends to hold the same in depressed position. The 65 plunger is provided with an extension 13 and a shoulder 14 forming an abutment which engages a ball detent 15 in the recess near the lower end of the projection 9. When the plunger is in depressed position, 70 as shown in Fig. 2, the abutment carried thereby forces the ball 15 partially out of its recess and in engagement with a shoulder 16 on a stationary magnetic core, said shoulder constituting a stationary abutment. The 75 forcing of the ball 15 partially out of its recess and into engagement with the shoulder 16 locks the remote-controlled switch closed and holds it in that position so long as the plunger 10 is in depressed position. 80

The remote-controlled switch, so far as described above, has already been described and claimed in my application No. 570,693, filed July 7th, 1910, and is shown and described in this application for the purpose 85 of describing my present improvement in connection therewith.

In order to provide means for releasing the switch arms I provide an armature 17, which, when the solenoid 17^a is energized, is 90 lifted so as to act through the pin 13 to raise the plunger 10 sufficiently to permit the balls 15 to reenter its recess. In order to control the circuit 13 in a proper manner, I provide contacts 18 mounted on a suitable 95 insulating base 19 and a movable switch arm 20 carried by a bushing 21 but insulated therefrom. This bushing 21 is mounted on a tubular member 22. This tubular member has a flange 23 and is engaged by a spring 24, which tends to force it upward so that the flange 23 engages the bushing 21 and lifts the switch arm 20, thereby separating it from the terminals 18. The spring 24 bears against an internal shoulder on the member 22. Upon the upper surface of the bushing 21 bears a spring 25, the upper end of this spring resting against a suitable abutment hereinafter described. When the remote-controlled switch is closed, the lower end of 105 110

the projection 9 engages the upper end of the tubular member 22, forcing it downward so as to tend to withdraw the flange 23 from the lower side of the bushing 21. The spring 5 25 thereupon pushes the bushing 21 downward so as to bring the switch arm 20 into engagement with the contacts 18-18 and thereby close the circuit of the solenoid 17^a. When the solenoid 17^a is energized, the 10 armature 17 acts to unlock the remote-controlled switch, whereupon the spring 24 raises the tubular member 22 so that the flange 23 engages the lower surface of the bushing 21 and lifts the switch arm 20, so as 15 to separate it from the contacts 18. The circuit through the solenoid 17^a is thereby made and broken at the proper times.

In order to close and open the circuit through the solenoids 8 at the proper times, 20 I mount upon the base 19 two other contacts 26-26, one of which is connected to one of the contacts 18, as shown in Fig. 5, and to a common source of current. For the contacts 26-26 I provide a second 25 switch arm 27 mounted on a removable bushing 28 so as to be carried thereby but insulated therefrom, said bushing being mounted upon the tubular member 22 above the bushing 21. This bushing 28 forms the 30 upper abutment for the spring 25, which, together with the spring 24, tend to make the bushing 28, together with its switch arm 27, move upward so that the switch arm 27 will engage the contacts 26. The armature 35 17 has an internal portion 17' connected thereto which depends so as to rest upon the bushing 28. This armature is provided with curved slots separated by a bridging portion 29. The upper end of the tubular member 22 is slotted so as to form two projections 22', which pass upward through the curved slots in the armature so as to be in position to be engaged by the lower end of the projection 9, the portion 29 of the armature lying between them being in position to engage or be engaged by the pin 13 of the plunger 10.

The action of the switch arm 26 is as follows: When the remote-controlled switch is 50 closed by the action of the solenoids 8, the projection 9, together with the plunger 10, is moved downward until the ball 15 reaches locking position. Thereupon the plunger 10 moves still farther downward, forcing 55 the ball into locking position and at the same time the lower end of the pin 13 engages the portion 29 of the armature, forcing it downward, together with the bushing 28 and the switch arm 27 carried thereby, separating the switch arm 27 from the contacts 26 and opening the circuit through the closing solenoids 8. It is to be noted that this circuit is not opened until the remote-controlled switch is fully locked, but upon 60 65 its being fully locked is immediately opened

by the positive action due to the spring 11. It has heretofore been pointed out that as the remote-controlled switch is closed, the projection 9 engages with the upper ends 22' of the tubular member 22, forcing it 70 downward so as to permit the switch arm 20 to engage the contacts 18. These contacts are in the circuit of the switch opening solenoid 17^a, and the engagement of the switch arm 20 therewith just prior to the complete 75 closing of the remote-controlled switch closes the circuit through the solenoid 17^a at the auxiliary circuit breaker, so that it is in condition to be energized by the local circuit controller at the desired remote point. 80 When the solenoid 17^a is subsequently energized, the armature 17 first forces up the plunger 10, releasing the detent 15, whereupon the remote-controlled switch opens and the lower end of the projection 9 is withdrawn from the upper end of the tubular member 22. This permits the switch arm 27 to engage the contacts 26, thereby closing the circuit through the solenoids 8. It also permits the switch arm 20 to be withdrawn from the contacts 18 by the spring 24, thereby opening the circuit through the solenoid 17^a, this opening taking place after the switch has been completely released. The springs 23 and 25 permit the tubular 90 member to have a movement independent of the movement of the switch arms 20 and 28, and also permit said switch arms to have movements independently of one another, thus producing a device in which the desired result will be accomplished without exceeding accuracy of the parts employed. The ends of the switch arms and the contacts engaged thereby are removed from all parts where burning would be liable to do 95 injury or interfere with the action of the auxiliary circuit breaker. Moreover, the contacts belonging to any one circuit are widely separated from one another and are broken by quick movements, so that sparking and its dangers are minimized. Moreover, the parts rigidly connected to the switch arm are none of them contained in either the switch closing or the switch opening circuit, the movements of these parts being utilized simply to actuate other parts having independent movement so as to bring about the desired result. 100

A diagram of circuit connections is shown in Fig. 7. In this diagram M-M' are two 105 mains leading from any suitable source and supplying translating devices L-L'. 2'-2'-2' are the main contacts connected to the mains M-M'-M², and 2-2-2 are the main switch contacts connected to the translating devices. 8-8 are the switch closing coils and 13 is the switch opening coil. 26-26 are the contacts in series with coils 8 and 18-18 are the contacts in series with the coil 17^a. Two of the contacts 18-18 are 110 115 120 125 130

connected to the main M by a common connection. The coils 8-8 are in series and their outside terminal forms a part of a local circuit controller L, which is connected to the main M². The free end of the solenoid 17^a is also connected to a terminal forming a part of this local circuit controller.

As will be evident to those skilled in the art, the embodiment of my invention permits of various modifications without departure from the spirit thereof or the scope of the appended claims.

What I claim is:

- 15 1. In a remote-controlled switch, the combination of an opening solenoid, contacts in the circuit thereof, a switch arm adapted to connect and disconnect said contacts, means tending to move said switch arm out of engagement with said contacts, a stationary base carrying said contacts and switch arm, said base being stationary relatively to the movable member of the remote controlled switch, said switch arm tending to move toward said movable member under the action of said spring and being movable relatively to said member and controlled thereby.
- 20 2. In a remote-controlled switch, the combination of an opening solenoid, contacts in the circuit thereof, a switch arm adapted to connect and disconnect said contacts and movable out of engagement therewith, a stationary base carrying said contacts and switch arm, said base being stationary relative to the moving member of the remote-controlled switch, means whereby said switch arm is controlled by said moving member, a member carrying said switch arm, a spring permitting said switch arm and member to have independent movements but tending to move said switch arm toward said contacts, and a second spring tending to move both said member and said switch arm away from said contacts against the action of said first
- 25 3. In a remote-controlled switch, the combination of an opening solenoid, contacts in the circuit thereof, a switch arm adapted to connect and disconnect said contacts and movable out of engagement therewith, a stationary base carrying said contacts and switch arm, said base being stationary relative to the moving member of the remote-controlled switch, means whereby said switch arm is controlled by said moving member, a member carrying said switch arm, a spring permitting said switch arm and member to have independent movements but tending to move said switch arm toward said contacts.
- 30 4. In a remote-controlled switch, the combination of an opening solenoid, contacts in the circuit thereof, a switch arm adapted to connect and disconnect said contacts and movable out of engagement therewith, a stationary base carrying said contacts and switch arm, said base being stationary relative to the moving member of the remote-controlled switch, means whereby said switch arm is controlled by said moving member, a member carrying said switch arm, a spring permitting said switch arm and member to have independent movements but tending to move said switch arm toward said contacts, and a second spring tending to move both said member and said switch arm away from said contacts against the action of said first
- 35 5. In a remote-controlled switch, the combination of an opening solenoid, contacts in the circuit thereof, a switch arm adapted to connect and disconnect said contacts and movable out of engagement therewith, a stationary base carrying said contacts and switch arm, said base being stationary relative to the moving member of the remote-controlled switch, means whereby said switch arm is controlled by said moving member, a member carrying said switch arm, a spring permitting said switch arm and member to have independent movements but tending to move said switch arm toward said contacts, and a second spring tending to move both said member and said switch arm away from said contacts against the action of said first
- 40 6. In a remote-controlled switch, the combination of an opening solenoid, contacts in the circuit thereof, a switch arm adapted to connect and disconnect said contacts and movable out of engagement therewith, a stationary base carrying said contacts and switch arm, said base being stationary relative to the moving member of the remote-controlled switch, means whereby said switch arm is controlled by said moving member, a member carrying said switch arm, a spring permitting said switch arm and member to have independent movements but tending to move said switch arm toward said contacts, and a second spring tending to move both said member and said switch arm away from said contacts against the action of said first
- 45 7. In a remote-controlled switch, the combination of an opening solenoid, contacts in the circuit thereof, a switch arm adapted to connect and disconnect said contacts and movable out of engagement therewith, a stationary base carrying said contacts and switch arm, said base being stationary relative to the moving member of the remote-controlled switch, means whereby said switch arm is controlled by said moving member, a member carrying said switch arm, a spring permitting said switch arm and member to have independent movements but tending to move said switch arm toward said contacts, and a second spring tending to move both said member and said switch arm away from said contacts against the action of said first
- 50 8. In a remote-controlled switch, the combination of an opening solenoid, contacts in the circuit thereof, a switch arm adapted to connect and disconnect said contacts and movable out of engagement therewith, a stationary base carrying said contacts and switch arm, said base being stationary relative to the moving member of the remote-controlled switch, means whereby said switch arm is controlled by said moving member, a member carrying said switch arm, a spring permitting said switch arm and member to have independent movements but tending to move said switch arm toward said contacts, and a second spring tending to move both said member and said switch arm away from said contacts against the action of said first
- 55 9. In a remote-controlled switch, the combination of an opening solenoid, contacts in the circuit thereof, a switch arm adapted to connect and disconnect said contacts and movable out of engagement therewith, a stationary base carrying said contacts and switch arm, said base being stationary relative to the moving member of the remote-controlled switch, means whereby said switch arm is controlled by said moving member, a member carrying said switch arm, a spring permitting said switch arm and member to have independent movements but tending to move said switch arm toward said contacts, and a second spring tending to move both said member and said switch arm away from said contacts against the action of said first
- 60 10. In a remote-controlled switch, the combination of an opening solenoid, contacts in the circuit thereof, a switch arm adapted to connect and disconnect said contacts and movable out of engagement therewith, a stationary base carrying said contacts and switch arm, said base being stationary relative to the moving member of the remote-controlled switch, means whereby said switch arm is controlled by said moving member, a member carrying said switch arm, a spring permitting said switch arm and member to have independent movements but tending to move said switch arm toward said contacts, and a second spring tending to move both said member and said switch arm away from said contacts against the action of said first

spring, and a locking device carried by said movable member adapted to compress said first spring when the movable member is in locked position.

4. In a remote-controlled switch, the combination of an opening solenoid, contacts in the circuit thereof, a switch arm adapted to connect and disconnect said contacts, a stationary base carrying said contacts and switch arm, said base being stationary relative to the moving member of the remote-controlled switch, means whereby said switch arm is controlled by said moving member, a member carrying said switch arm, a resilient means permitting said switch arm and member to have independent movements but tending to move said switch arm toward said contacts, a second resilient means tending to move both said member and said switch arm away from said contacts against the action of said first resilient means, a second switch arm carried by said member and separated from said first switch arm by said first mentioned resilient means, switch closing contacts adapted to be engaged thereby, and switch locking means for said remote-controlled switch adapted to separate said last switch arm from its contacts when said remote-controlled switch is locked.

5. In a remote-controlled switch, the combination of an opening solenoid, contacts in the circuit thereof, a switch arm adapted to connect and disconnect said contacts, a stationary base carrying said contacts and switch arm, said base being stationary relative to the moving member of the remote-controlled switch, means whereby said switch arm is controlled by said moving member, a member carrying said switch arm, a resilient means permitting said switch arm and member to have independent movements but tending to move said switch arm toward said contacts, a second resilient means tending to move both said member and said switch arm away from said contacts against the action of said first resilient means, a second switch arm carried by said member and separated from said first switch arm by said first mentioned resilient means, switch closing contacts adapted to be engaged thereby, and switch locking means for said remote-controlled switch adapted to separate said last switch arm from its contacts when said remote-controlled switch is locked, and an armature for releasing said lock, said armature having a portion interposed between said lock and said switch arm.
